UNITED STATES PATENT OFFICE.

JAMES T. BRACHT, OF MEMPHIS, TENNESSEE.

ARTIFICIAL LIMB.

1,155,545.

Specification of Letters Patent.

Patented Oct. 5, 1915.

Application filed February 20, 1915. Serial No. 9,756.

To all whom it may concern:

Be it known that I, JAMES T. BRACHT, a citizen of the United States, residing at Memphis, in the county of Shelby and State 5 of Tennessee, have invented certain new and useful Improvements in Artificial Limbs, of which the following is a specification.

The present invention relates to improvements in artificial limbs, and relates more 10 particularly to the ankle joint thereof, one object of the invention being the provision of a joint that permits of a natural movement of the joint, and which is further provided with means whereby the same is automatically lubricated to prevent squeaking 15 during the movement of the limb.

A further object of the invention is the provision of an ankle joint, which is simple, durable and inexpensive in construction and 20 which is thoroughly efficient and practical in use.

With the foregoing and other objects in view that will appear as the description proceeds, the invention consists in the construction and combination of parts as particularly pointed out in the claims.

In the accompanying drawings:—Figure 1 is a side elevation of the lower portion of an artificial limb in section with the present 30 joint in use. Fig. 2 is a front elevation of the joint *per se*. Fig. 3 is a section on line 3—3 of Fig. 2. Fig. 4 is a view of a modified form. Fig. 5 shows two parallel rods passing through the foot.

Referring to the drawings, the numeral 5 designates the foot and 6 the lower section of an artificial limb or leg, the ankle joint 7 being employed as the connection between the two.

The joint comprises essentially the member 8, which fits within and engages the section 6, and is provided with the transversely disposed cylindrical end 9, which is provided with the cylindrical bore 10. The upper 45 end is threaded as at 11 for the reception of the attaching nut 12.

The member 13 of the joint is provided with the enlargement 14, having the cen-

tral recess or slot 15 for the reception of the end 9 of the member 8, the two cylindrical members 16 thereof being provided with cylindrical bores 17 that align and also align with the bore 10, so that the tubular member 18 may be passed through all the bores from one of the members 16. This 55 member 18 is provided with the annular rim or flange 19 of substantially the same diameter as the member 16, and has its opposite end terminating flush with the outer face of the other member 16, the same being 60 provided with the interior threads 20 for the reception of the securing screw 21, whose head 22, fits exteriorly of the adjacent member 16 and is of substantially the same diameter as the member 16. This head 22 65 when the parts are assembled fits flush against the end of the member 18 and slightly spaced from the member 16, so as to permit the necessary flexing at this point.

The member 18 constitutes a lubricant 70 holder and is provided with openings 23 through which the lubricant is automatically supplied to the members 9 and 16.

As shown in Figs. 1 and 2 the member 13 is a single rod threaded at 24 to receive a 75 nut 25, whereas in Fig. 5 two parallel rods 26 are employed.

From the foregoing description, it is evident that a simple and durable ankle joint is provided and that with the lubricating feature a great objection to joints is overcome.

What is claimed, as new, is—

1. An ankle joint for artificial limbs, including two coöperating members, one of which is provided with a single hollow cylindrical end, while the other of which is provided with two hollow cylindrical ends for axial alignment with the other hollow end, and a tubular fastening and bearing member fitting in all the hollow ends and 90 upon which the ends rotate.

2. An ankle joint for artificial limbs, including a foot engaging and a lower limb engaging member, a hollow cylindrical knob carried by one member, two hollow cylindrical knobs carried by the other member,

said knobs being spaced apart to permit the insertion therebetween and axially aligned therewith of the first knob, a tubular member sealed at one end and having an annular 5 rim at the sealed end said tubular member fitting in the hollows of the knobs and forming a bearing for the knobs, and a locking member insertible in the open end of the

tubular member for locking the parts assembled.

In testimony whereof I affix my signature in presence of two witnesses.

JAMES T. BRACHT.
